UNITED STATES PATENT OFFICE.

ELLIOTT J. STODDARD, OF DETROIT, MICHIGAN, ASSIGNOR TO THE FREE-PISTON GAS ENGINE COMPANY, OF DETROIT, MICHIGAN.

GAS-ENGINE.

SPECIFICATION forming part of Letters Patent No. 781,751, dated February 7, 1905.

Application filed December 10, 1900. Renewed July 8, 1904. Serial No. 215,728.

To all whom it may concern:

Be it known that I, ELLIOTT J. STODDARD, a citizen of the United States, residing at Detroit, county of Wayne, State of Michigan, have invented a certain new and useful Improvement in Gas-Engines; and I declare the following to be a full, clear, and exact description of the invention, such as will enable others skilled in the art to which it pertains to make and use the same, reference being had to the accompanying drawings, which form a part of this specification.

My invention relates to gas-engines; and it consists in the improvements hereinafter described.

Referring to the accompanying drawings, Figure 1 is a side elevation of a gas-engine embodying my invention, and Fig. 2 is a plan thereof, the cylinder and valve cases being shown in section.

The same letter indicates the same part in both views.

A is the bed-plate; C, the cylinder; D, the crank-shaft; E, the fly-wheel; F, the connecting-rod; G, the cross-head; H, the piston, and I the piston-rod. The piston-rod passes through a stuffing-box *j* in the crank end of the cylinder and through an aperture in the cross-head.

B is a clutch upon the cross-head, adapted to engage the piston-rod I to prevent an independent movement of said piston-rod relative to the cross-head in a direction toward the left of the figures, but to permit a relative movement in the other direction. The clutch B is secured to a rock-shaft *b*, which rests in bearings on the cross-head. On an outer end of the rock-shaft *b* is secured a lever-arm J.

j is a spring acting to press the clutch B against the rod I. The connecting-rod F is pivoted at *f* to the cross-head G.

K is a finger extending from the connecting-rod F near the pivot-point *f* and adapted at a certain angular position of the connecting-rod to contact the lever-arm *b* and lift the clutch B out of contact with the piston-rod.

L (shown in dotted lines, Fig. 1) is a tank for compressed air, which communicates with the cylinder C in front of the piston through

a passage or passages *m m*. The tank L is 50 made so large that the pressure therein will not increase very much on the outstroke of the piston.

M is a tank for compressed explosive mixture. 55

N is a pump adapted to supply compressed explosive mixture to the tank M.

n is a pipe connecting the tank M with the cylinder C behind the piston H.

P is the inlet-valve, and *p* the exhaust-valves, 60 which may be operated by eccentrics from the engine-shaft.

I have shown the tank L connected with the tank M by a pipe *n*, it being understood that there is a non-return valve in said pipe, 65 and this valve would be so adjusted as to keep the pressure in the tank L a little below that in the tank M—say five pounds. This arrangement is here adopted for convenience of illustration. Other arrangements for adjusting the pressures may be substituted. 70

The operation of the above-described device is as follows: The fly-wheel is turning in the direction of the arrow. When in the position shown in Fig. 1, the finger K contacts the lever-arm J, rocking the shaft *b* and raising the clutch from the piston-rod I. As the fly-wheel E continues its motion the clutch is held out of engagement and the cross-head drawn forward until the latter has reached 80 the forward end of the stroke, when the finger K is again turned out of engagement with the lever-arm J, allowing the clutch to again engage with the piston-rod. Meanwhile a charge of compressed explosive mixture has 85 been admitted behind the piston, and just after the clutch B has reengaged the piston-rod the charge is fired, driving the piston H rapidly forward against the pressure in the tank L. As soon as the piston H has reached the forward end of its stroke and begins to return it engages the clutch B and the power of the explosion stored in the motion of the piston against the pressure in the tank L is given out and communicated to the shaft and fly-wheel E during the return stroke of the engine. 90

The tank M has been made small, so that the withdrawal of one charge therefrom into

the cylinder C will lower the pressure in said tank to about that in the tank L, so that the piston H will come to rest with the proper amount of explosive mixture behind it. Other methods for accomplishing this purpose will readily occur to those conversant with the art.

The electric ignition may be actuated from any of the moving parts of the engine in the usual ways.

- 10 It will be observed that the parts actuated by the explosion move very quickly, allowing but a very brief time for the heat to radiate to the cylinder, that the expansion will be to a pressure considerably below atmosphere, 15 thus reducing the loss of heat in the exhaust-gases, that the quickly-moving parts are rigidly connected together, so as to avoid joints and lost motion, and that the valves may be actuated directly by eccentric-rods operated 20 by the crank-shaft.

What I claim is—

- 1. In a gas-engine, the combination of a cross-head, a connecting-rod pivoted to said cross-head and to the engine-crank, a piston-rod 25 arranged to slide through said cross-head, a clutch upon said cross-head adapted to prevent a motion of said piston-rod in one direction relative to said cross-head but to permit such motion in the other direction, and means 30 for lifting said clutch out of engagement with said piston-rod during the motion of said cross-

head in one direction, substantially as described.

2. In a gas-engine, the combination of a cross-head, a connecting-rod pivoted to said 35 cross-head and to the engine-crank, a piston-rod arranged to slide through said cross-head, a clutch upon said cross-head adapted to prevent a motion of said piston-rod in one direction relative to said cross-head, but to permit 40 such motion in the other direction, a portion of said connecting-rod being adapted to contact and disengage said clutch when said connecting-rod is upon one side of its central position, substantially as and for the purpose 45 described.

3. In a free-flying piston-engine, a piston adapted to move in one direction under the influence of the explosion, means for retracting the piston, a rotating part adapted to be 50 actuated by the piston on its return motion, and means whereby the rotation of said rotating part acts to connect the same with the piston on its return stroke and to disconnect said rotating part from the piston on the forward movement of the same.

In testimony whereof I sign this specification in the presence of two witnesses.

ELLIOTT J. STODDARD.

Witnesses:
